Augustus Mathews
Design for a Reflector

United States Patent Office.

AUGUST WILHELM, OF PHILADELPHIA, PENNSYLVANIA.

Design No. 2,857, dated December 31, 1867.

DESIGN FOR A REFLECTOR.

The Schedule referred to in these Letters Patent and making part of the same.

TO ALL WHOM IT MAY CONCERN:

Be it known that I, AUGUST WILHELM, of the city of Philadelphia, in the State of Pennsylvania, have invented or produced a new and original Design for a Light-Reflector for Lamps, Street-Lanterns, &c., of which the following is a clear and exact description, reference being had to the accompanying drawings, making a part of this description, and to the letters of reference marked thereon. Referring to the drawings—

Figure 1 is a front representation of the reflector, and

Figure 2 a vertical longitudinal section through the centre of the said reflector, $a\ a$ being the back portion of the reflector, and $a\ b\ a\ b$ the sides of the same.

The inside or reflecting-surfaces of $a\ a$ and $a\ b\ a\ b$ are each parts of hyperbolic curves, arranged in relation to each other as shown in the drawings. The intersections of the faint lines radiating from the points $x\ y\ z$ give the form required for the respective reflecting-surfaces of the reflector, $a\ a$, $a\ b$, $a\ b$, and also the resultant directions of the rays of light coming from z . The said radiating lines are merely illustrative of the forms of the reflecting-surfaces of the reflector, and of their relation to each other, as shown, and therefore form no part of the design; but having shown and described the particular form of the reflector, $a\ a$, $a\ b$, $a\ b$,

What I claim as my invention or production, and desire to secure by Letters Patent, is—

The design for a reflector, herein shown and described.
